UNITED STATES PATENT OFFICE.

RICHARD COLBERT MASON, OF TULSA, OKLAHOMA.

WELL-MEASURING DEVICE.

1,408,113.

Specification of Letters Patent. Patented Feb. 28, 1922.

Application filed January 28, 1921. Serial No. 440,664.

To all whom it may concern:

Be it known that I, RICHARD C. MASON, a citizen of the United States, and a resident of Tulsa, in the county of Tulsa and 5 State of Oklahoma, have invented certain new and useful Improvements in Well-Measuring Devices, of which the following is a specification.

This invention relates to geometrical instruments especially adapted for ascertaining the depth of wells and the like.

An important object of this invention is to provide a measuring device which may be conveniently mounted on the upper end 15 of the well casing and engaged with the cable of the drill or the sand line for indicating to the attendant the distance which the cable extends into the well.

A further object is to provide a device of 20 the class described which is simple to operate, accurate in use and cheap to manufacture.

Other objects and advantages of the invention will be apparent during the course 25 of the following description.

In the accompanying drawings forming a part of this application and in which like numerals are employed to designate like parts throughout the same

30 Figure 1 is a side elevation of the improved measuring device in use.

Figure 2 is a vertical transverse sectional view taken on line 2—2 of Figure 1.

Figure 3 is a detailed horizontal sectional 35 view taken on line 3—3 of Figure 1.

Figure 4 is a detail sectional view illustrating the means for connecting the screw to the head.

In the drawing wherein for the purpose of illustration is shown the preferred embodiment of the invention, the numeral 5 generally designates the frame of the apparatus or measuring device, which frame is preferably cast in a single piece and includes spaced sides 6 and 7 and end pieces 8 and 9.

The end pieces 8 and 9 of the frame are formed with aligned recesses or openings 10 for the reception of the cable 12 of the well 50 drilling apparatus. As illustrated in Figures 1 and 2 the cable 12 extends through the aligned openings 10 and is held within the opening by means of pivoted latches or keepers 14 which extend across one side of the opening and thereby retain the cable within the opening. When desired, how-

ever, the cable may be removed from the opening by elevating the latches 14 whereupon the device may be moved laterally away from the cable.

60 A pair of spaced parallel bearing plates 15 are secured at their ends to opposite sides or edges of the end pieces 8 and 9 and as illustrated in Figure 2 the plates 15 receive the reduced end portions of the supporting 65 axles 18 of a plurality of pulleys or grooved wheels 20. The grooved wheels 20 which are arranged between the bearing plates are all arranged in the same vertical plane and are adapted to be engaged with the cable 70 12 so that as the cable is moved longitudinally the wheels will all be rotated in the same direction.

A sprocket wheel 22 is rigidly secured on each axle 18 and is engaged by a continuous 75 sprocket chain 24 which causes all pulley wheels to rotate together and in the same direction.

The reduced end portion 26 of the intermediate axle is extended beyond one of the 80 bearing plates 15 and is adapted to be connected with the operating member 28 of a length indicating register 30. The register 30 which is clearly illustrated in Figure 2 may be of any type and is provided with 85 attaching arms 32 having laterally projecting terminal portions secured to one of the bearing plates 15 by means of fastening devices 34. The meter 30 may of course be readily detached when desired.

90 A pair of tensioning pulleys 36 are arranged on one side of the cable to contact with the same and are adapted to move the cable firmly into contact with the pulleys 20 so that the pulleys 20 will be caused to rotate when the cable 12 is raised or lowered in the well. As illustrated in Figure 1, the tensioning members 36 are arranged in planes which extend between the pulleys 20 so that the cable will be caused to curve 100 somewhat about the peripheries of the pulleys.

105 Tensioning pulleys 36 are carried by a triangular head 39 which is operated by means of a screw 40 having rigid connection with an operating crank 41. The screw 40 extends through a bracket 42 and through the side piece 7 of the frame. The head 39 of the tensioning rollers or wheels 36 is passed between a pair of guide plates 45 110 which are secured on opposite sides of the frame by means of fastening devices 46.

In use the handle of the crank 41 is rotated by the operator so as to advance the screw 40 whereupon the head 39 and the rollers are advanced. When the rollers 36 5 are thus advanced the cable 12 is urged into engagement with the rollers 20 whereby the longitudinal movement of the cable 12 will result in the rotation of the rollers. Of course, any desired tension may be applied to the cable 12 by merely adjusting the screw 40 by means of the hand operated crank 41. It will be observed that the guide plates 45 secured on opposite sides of the frame prevent the head from rotating about 10 the longitudinal axis of the screw 40 when the screw is rotated.

The improved meter may be arranged on the upper end of the well casing 50 for measuring the depth of the well either during insertion or removal of the cable. 20

Of course, when the device is attached prior to withdrawing the cable, the same is arranged in a position opposite that from where the device is attached prior to the 25 insertion of the cable. The cable is engaged with the grooved rollers 20 by moving the tensioning rollers 36 firmly into contact with the cable. When one of the rollers 20 fails to rotate by the movement of the 30 cable, the other rollers will by reason of the friction be engaged with the tensioning means and be rotated so that all of the rollers 20 will be rotated together.

As illustrated in Figure 4 a coiled spring 35 60 mounted on the operating screw 40 is confined between the rear side of the head 39 and an annular member 62 securely connected to the screw. It is thus seen that the operating screw 40 is freely movable 40 through the head 39 and that the coiled spring 60 provides a yieldable driving connection between the feed screw 40 and the head 39. The head 39 and the rollers 36 carried thereby are yieldably urged into position and when an enlargement on the rope 45 or cable 12 strikes the wheel 36, the head 39 moves rearwardly to a limited extent.

Having thus fully described my invention what I claim as new and desire to secure 50 by Letters Patent is:—

1. A measuring device comprising a frame having bearing plates, pulleys carried by said plates, means connecting the pulleys, a head having a plurality of rollers adapted 55 for urging a cable into driving engagement

with said pulleys, a tensioning screw threaded through said frame and connected to said head, and a hand operated crank rigidly connected to said screw and adapted to be rotated for urging said tensioning rollers in the direction of said pulleys. 60

2. A measuring device for wells comprising a frame, pulleys carried by said frame, a head having rollers adapted for urging the cable into driving engagement with said 65 pulleys, a tensioning screw threaded through said frame and connected to said head, a crank connected to said screw and adapted to be rotated for urging said rollers in the direction of said pulleys, and means secured to said frame for guiding the rollers of the same. 70

3. A measuring device for wells comprising a frame, pulleys carried by said frame, means connecting the pulleys, a head having a plurality of rollers adapted for urging a cable into driving engagement with said 75 pulleys, a tensioning screw threaded through said frame and connected to said head and having means whereby the same may be rotated for advancing said head in the direction of said pulleys, means secured to said frame on opposite sides of said head for guiding the head, and a guide bracket secured to said frame and having an opening 80 receiving said screw. 85

4. A measuring device comprising a frame having oppositely arranged bearing plates, pulleys carried by said plates, means connecting the pulleys, a head having rollers 90 adapted for urging a cable into driving engagement with said pulleys, a tensioning screw threaded through said frame and connected to said head, means connected to said screw and adapted to be rotated for urging 95 said tensioning rollers in the direction of said pulleys, and a length indicating register operated by one of said pulleys.

5. A well measuring device comprising a frame, a pulley carried thereby, a tensioning head having rollers arranged adjacent opposite sides of said pulley and adapted for urging the cable into driving engagement with the pulley, a tensioning screw threaded through said frame and connected to said 100 head, a guide bracket carried by said frame and having an opening receiving said tensioning screw, and guiding means for said head. 105

RICHARD COLBERT MASON.
